UNITED STATES PATENT OFFICE.

AUGUSTUS G. SNYDER, OF UTICA, NEW YORK, ASSIGNOR OF ONE-HALF TO ROBERT T. THOMAS, OF UTICA, NEW YORK.

TYPE-WRITER.

1,070,549.

Specification of Letters Patent. Patented Aug. 19, 1913.

Application filed December 27, 1909. Serial No. 535,139.

To all whom it may concern:

Be it known that I, AUGUSTUS G. SNYDER, a resident of Utica, in the county of Oneida and State of New York, have invented certain new and useful Improvements in Type-Writers; and I do hereby declare that the following is a full, clear, and exact description thereof, which will enable others skilled in the art to which it appertains to make 5 and use the same, reference being had to the accompanying drawings, and to the reference-numerals marked thereon, which form part of this specification.

The object of my invention is to provide 15 an improved form of typewriter wherein the practice heretofore pursued of either shifting the platen or shifting the type bar basket to bring into operation the upper or lower case of letters is obviated, and a machine produced which is simple and effective 20 and well adapted to meet the requirements of a typewriting machine.

Figure 1 shows a vertical sectional view 25 of a typewriter embodying features of my construction. Fig. 2 is a partial plan view of a typewriter machine embodying the features of my construction.

Referring to the reference letters and figures in a more particular description, 30 indicates the frame of a typewriting machine, which may be of the usual construction and which is provided particularly with the segment 11 on which the hangers 12 carrying the type bars 13 pivotally mounted 35 at 14 therein are supported. At the swinging end the type bars 13 are adapted in normal position to be supported on a semi-circular rest 15 and are adapted to describe an arc of about 90 degrees in moving from 40 the rest to their printing position on the face of the platen 16. The type bars 13 are provided with a bell crank portion to which one end of the connecting rod 17 is attached, while the other end of the connecting rod 45 17 attaches to one arm of the bell crank lever 18 mounted on a fixed bearing at 29 in the frame. The opposite end of the bell crank lever 18 is connected by a connecting rod 19 with one end of the slotted link 20. 50 The opposite end of the slotted link 20 is connected by another connecting rod 19^a with a bell crank lever 18^a similar to and next adjacent to the one shown in Fig. 1 and connected by a connecting arm as 17^a with 55 the next adjacent type bar 13^a to the one

shown in Fig. 1. The slotted link 20 is connected by a link or connection 21 from a point at or near its middle with the key lever 22. Extending longitudinally through the series of links 20 provided on the machine is a rod 23, which serves as a fulcrum for the link and is mounted at each end in the swinging ends of levers 24, which levers are pivotally mounted and rigidly secured to a rock shaft 25 mounted in bearing in the frame. The levers 24 are adapted to be operated by a shift key lever 26, the same engaging with a bell crank lever portion of the arm 24. The type bars 13 and 13^a are intended to carry upper and lower case type, 70 respectively. The link 20 is provided at one end with a segmental slot through which is passed a fixed bar 27 supported in the frame and which serves to prevent longitudinal movement of the link 20. 75

The operation of the construction is as follows: When the shift key of the lever 26 is in its upper position, as shown in Fig. 1, the pivot rod or bar 23 will be in the right-hand end of the slot link 20 as the parts are shown in Fig. 1. If the key lever 22 be now operated by depressing the key through the medium of the link or connection 21, the left-hand end of the link 20 will be moved down swinging on the bar 23 as a pivot, the link 19^a will become effective to operate the type bar 13^a. At the same time the link 19 will not be operative; likewise the type bar 13. By depressing the shift key lever 26 the arms 24 carrying the bar 23 will be 85 swung over into the position shown in dotted lines in Fig. 1. The link 20 will not be allowed to move or follow in this movement on account of being held by the fixed bar 27. If in the shifted position mentioned, 90 the key lever be now depressed the right-hand end of the link 20 will be moved down and the type bar 13 operated through the medium of the link 19 and the bell crank lever 18 and the other connection. The segmental slot in which bar 27 engages permits 95 the swinging movement of the link in the operation last described. In making the shift from the upper to the lower case, or vice versa, with the mechanism herein shown and described there is very little weight or mechanism to be moved, simply either of the shift levers 26, the arms 24 and the fulcrum bar 23. 100

It is evident that modifications and 110

changes in and from the construction herein described may be made without departing from my invention or the subject matter intended to be covered by the claims.

5. What I claim as new and desire to secure by Letters Patent is:

1. The combination in a typewriter of two type bars, a single key lever, a slotted link, connections from each end of said link to one of the said type bars, a fulcrum movable longitudinally in said slotted link and adapted to lock either end of said link from operation and means connected to said key lever and separate from said fulcrum moving means for operating said slotted link.
10. 2. In an action mechanism for typewriters the combination of a set of type bars, a set of key levers, connections from each key lever to two type bars, said connections including a slotted link and a movable fulcrum on which the link is mounted, and a key shifting lever for moving said fulcrum, substantially as set forth.
15. 3. In an action mechanism for typewriters the combination of a set of type bars, a set of key levers, connections from each key lever to two type bars, said connections including a slotted link and a movable fulcrum on which the link is mounted, and means for holding said link from longitudinal movement with said fulcrum, substantially as set forth.
20. 4. The combination in a typewriter of

two type bars, a single key lever, a slotted link, connections from each end of said link to one of the said type bars, a connection from the center of said slotted link to the key lever and a fulcrum movable longitudinally in said slotted link, and adapted to lock either end of said link from operation, substantially as set forth.

5. The combination in a typewriter of two type bars, a single key lever, a slotted link, connections from each end of said link to one of said type bars, a connection from the center of said slotted link to the key lever, a fulcrum movable longitudinally in said slotted link and adapted to lock either end of the said link from operation, and a key lever for operating said fulcrum, substantially as set forth.

6. The combination in a typewriter of two type bars, a single key lever, a slotted link, connections from each end of said link to one of the said type bars, a connection from the center of the said slotted link to the key lever, a fulcrum movable longitudinally in said slotted link and adapted to lock either end of said link from operation and a stop holding said link from longitudinal movement with the said fulcrum, substantially as set forth.

AUGUSTUS G. SNYDER.
